UNITED STATES PATENT OFFICE

NAT P. STECKLER, OF NEW YORK, N. Y.

DESIGN FOR A COMBINED EYEGLASS CLEANER AND POLISHER AND CONTAINER THEREFOR

Application filed September 28, 1931. Serial No. 41,253. Term of patent 14 years.

To all whom it may concern:

Be it known that I, NAT P. STECKLER, a citizen of the United States, residing at New York, in the county of New York and State of New York, have invented a new, original, and ornamental Design for Combined Eye-glass Cleaner and Polisher and Container. Therefor, of which the following is a specification, reference being had to the accompanying drawings, forming part thereof.

Fig. 1 is a top plan view of a combined eye-

glass cleaner and polisher and container therefor.

Fig. 2 is a front elevation thereof.

Fig. 3 is a front elevation of the top and bottom parts of the casing, separated.

I claim:

The ornamental design for a combined eye-glass cleaner and polisher and container therefor, as shown.

NAT P. STECKLER.
